(57) CLAIM

The ornamental design for a gutter clearing device, as shown and described.

DESCRIPTION

FIG. 1 is a top perspective view showing my new design; FIG. 2 is a bottom perspective view thereof;

FIG. 3 is a top view thereof;

FIG. 4 is a front view thereof;

FIG. 5 is a bottom view thereof;

FIG. 6 is a rear view thereof;

FIG. 7 is a left side view thereof;

FIG. 8 is a right side view thereof;

FIG. 9 is a bottom perspective view thereof shown in a position of use; and,

FIG. 10 is a bottom perspective view thereof shown in a position of use with the door open.

The broken lines shown in the drawings depict portions of the gutter clearing device that forms no part of the claim. The broken lines shown in FIGS. 9 and 10 are for the purpose of illustrating environment only and form no part of the claim.
